UNITED STATES PATENT OFFICE.

PAUL JONES, OF WHITMAN, MASSACHUSETTS, ASSIGNOR TO COMMONWEALTH SHOE AND LEATHER COMPANY, OF WHITMAN, MASSACHUSETTS, A CORPORATION OF MASSACHUSETTS.

FOOT-MEASURING DEVICE.

Application filed September 15, 1927. Serial No. 219,617.

This invention relates to a device for measuring feet in order to expedite the fitting of footwear in shoe stores and the like.

Heretofore measuring devices of this character have ordinarily been provided with means for determining the overall length of the foot. It has thus been necessary for the shoe salesman to depend upon the measure of the overall length in selecting shoes to be tried upon the foot. However, the lasts upon which shoes are formed are generally classified by sizes not primarily in accordance with their overall lengths, but rather in accordance with the distances between the extremities of the heel portions and the portions corresponding to the ball joint of the foot. For example, in a single size of shoe the overall length varies considerably with shoes of various widths and with various styles of lasts. Thus lasts or shoes of the same size may have various overall lengths and widths, but generally have the same dimensions between the heel and ball joint portions. Accordingly, the overall length of the foot shown by the ordinary measuring devices serves only roughly to indicate the proper size of shoe.

The device disclosed herein is designed to obviate these difficulties and immediately to provide an accurate indication of the actual size of shoe which will fit a person's foot. Thus the fitting of shoes is expedited, the time of salesmen and purchasers is conserved, while oftentimes a more satisfactory fit is obtained. To this end, the present invention comprises a device provided with a part to fit against the back of the heel or the heel cord, and a part to engage and be substantially centered in relation to the ball joint of the foot. Furthermore, the device is provided with a suitable scale which permits the direct reading of the size of the shoe which corresponds to the dimensions of the foot thus measured. It is possible for a salesman with a device of this character quickly and accurately to determine the size of shoe which will fit a customer, and it then only remains necessary to determine the particular width of shoe which will conform to the customer's foot.

The above and further objects and advantageous features of this invention will be

apparent to those skilled in the art upon a reading of the subjoined description and claim in conjunction with the accompanying drawings, in which:

Fig. 1 is a side elevational view of the improved measuring device as applied to a human foot, which is shown in dot and dash lines;

Fig. 2 is a top plan view of the device; and

Fig. 3 is an enlarged sectional detail on line 3—3 of Fig. 1.

The improved measuring device, which is exemplified by the accompanying drawings, comprises a measuring stick 1 with a recessed portion, the latter preferably being formed by the cupped member 2 secured to the end of stick 1. This member may be made from a sheet metal disk shaped to resemble a portion of the surface of a sphere, and may be of a suitable size approximately to fit and be centered in relation to the ball joint or bit toe joint of a human foot.

Slidably mounted upon the stick 1 is a movable heel-engaging member 3. This slide preferably has an upstanding portion 4 with a vertical surface 5 adapted to engage the back of the heel. Member 4 is provided with side plates 6 which have inturned lower marginal portions 7 adapted slidably to engage the longitudinal grooves 8 in the side of stick 1 so that the surface 5 remains substantially at right angles to the plane of the stick.

One of the plates 6 is cut away to receive suitable frictional retaining means 10 for the slide 3. This means comprises the sheet metal member 11 having inwardly extending ears 12 which pivotally engage the body portion of member 3, as designated by numeral 13. The upper end of the member 11 is urged outwardly by the coil spring 14 which engages the plate 6 at the opposite side of the device, while the lower end of member 11 frictionally engages the side of stick 1 to hold the member 3 in the desired adjusted position.

A stop 15 projects upwardly from the upper surface of stick 1 in order to limit the outward movement of member 4 to prevent accidental removal of the latter from stick 1. A suitable opening 16 may be provided adjoining this stop to permit convenient

hanging of the device upon a hook or the like. The upper surface of stick 1 is provided with a series of graduations, designated in general by the numeral 20, and 5 disposed in the region which the heel slide will normally occupy when the device is being used. The divisions of this scale are provided with suitable numerals to indicate the shoe sizes corresponding to the various 10 relative positions of the surface 5 of the slide and the cup.

In the use of a device of this character, the foot is placed upon the upper surface of member 1 and the ball or big toe joint of 15 the foot is centered in relation to cup 2, as indicated by the dot and dash line showing of Fig. 1, the shape of this cup being particularly advantageous in permitting this operation to be performed with satisfactory 20 accuracy by a person having a moderate amount of experience in using this measuring device. The member 3 is then moved to a position wherein the surface 5 engages the back of the heel or the heel cord. It is 25 evident that the member 3 may be slid by releasing the member 11 from frictional engagement with the stick 1, this action being effected by applying pressure to the upper portion of member 11 and compressing 30 spring 14. After slide 3 has thus been properly located in relation to the heel, the foot 35 is removed from the device and the position of surface 5 upon scale 20 provides an accurate indication of the size of shoe which will fit the foot that has just been measured. It

then remains only necessary to determine the width of the shoe in the desired style by trial aided by the experienced judgement of the shoe salesman or in any desired manner. It is furthermore obvious that this device 40 may be used in conjunction with or in combination with other means for determining the width of shoe which will fit the foot that is being measured.

I claim:

A foot measuring device comprising an elongate stick, a sheet-metal cup with its inner surface having a curvature substantially corresponding to that of a sphere, 50 said cup being secured adjoining the upper surface of the stick near one end thereof, said stick having a width adjoining the cup less than the width of the cup, an upright slide movably mounted upon the stick, manually operable means for selectively releasing the slide from a normally locked position upon the stick, a surface of the slide being substantially vertical to the plane of the stick to engage the heel of a foot, the upper and lower surfaces of said 55 stick being substantially flat and the lowest point within the cup being substantially on a level with the upper surface of the stick so that a foot thereon may be substantially horizontal, and a scale of foot sizes upon 60 the upper face of the stick.

Signed by me at Whitman, Massachusetts, this 12th day of September, 1927.

PAUL JONES.
